UNITED STATES PATENT OFFICE

LOUIS A. M. PHELAN, OF ELKHART, INDIANA, ASSIGNOR TO TIME-O-STAT CONTROLS COMPANY, OF ELKHART, INDIANA, A CORPORATION OF INDIANA

ADJUSTING MEANS FOR TILTABLE SWITCHES

Application filed December 22, 1926. Serial No. 156,346.

This invention relates to tilttable switches and has special reference to adjustable means for regulating the time of actuation of such switches.

Hereinafter, this invention will be described in connection with a pressure switch employing a liquid electrical contactor tube comprising a container for enclosing a pair of electrodes or conducting terminals and a coherent body of current-conducting fluid through the agency of which fluid said electrodes are brought into electrical conducting relation with one another.

In a switch of the type above mentioned, it is particularly desirable to obtain a very close control of the actuation thereof and, moreover, to be able to adjust this control very accurately.

One of the objects of this invention is to provide an adjusting means for a switch as indicated above which adjusting means will be positive in operation and will permit of a wide range of pressure to be exerted upon a pressure responsive device within a pressure switch.

A further object of this invention is to provide a simple adjusting means for accurately controlling the necessary amount of effective pressure required to actuate the contactor tube of a pressure switch.

Further objects of this invention will be apparent from the description and drawings forming a part of this specification to which reference may now be had for a more complete understanding of the characteristic features of this invention.

Figure 1 is a front elevational view of a mercury tube pressure switch showing the cover removed;

Fig. 2 is a side elevational view showing the housing in section;

Fig. 3 is a front elevational view of a portion of the device showing a changed position of the actuating elements; and

Fig. 4 is a side elevational view of a portion of the device showing in particular the graduated scale of the adjusting screw.

Referring more particularly to the drawings, the switch in general comprises a liquid contactor tube which is mounted on a suit-

able supporting and tilting mechanism which latter is operated by a pressure controlled member, in this instance a diaphragm, said contactor tube serving to make and break an electrical circuit.

The contactor tube 10 comprises a container 11 in which two spaced electrodes 12 and 13 are hermetically sealed and in which a body of current conducting fluid 14 is disposed serving to bridge said electrodes thus establishing an electric circuit through the contactor. The electrodes 12 and 13 are adapted to be connected to an external electrical circuit by means of leads 15 and 16 extending therefrom to be secured to binding posts 17 and 18, respectively, mounted on a terminal board 19. The terminal board 19 is disposed within the casing and is suitably secured by means of screws to projections extending from the back wall of said casing. Wires may be fastened to a pair of binding posts 17^a and 18^a similar to binding posts 17 and 18 and connected thereto through contact strips, said wires to be led to the exterior of the casing to an opening 21^a which is of sufficient size to provide for the usual electrical wiring conduit.

An operating mechanism 20 is provided to engage the contactor tube 10 and is disposed within a casing 21, which casing in turn is mounted upon a diaphragm chamber 22. The contactor tube is mounted in a spring clip 23, which is attached to a collar 24 tiltably mounted on a pin 25 secured to the casing 21. The collar 24 has an operating arm 26 preferably integral therewith and extending transversely thereto.

The operating mechanism 20 comprises a tilting actuator 27 preferably made of a sheet metal stamping and which is pivotally mounted at its lower end upon a projection 28 extending from the casing 21. A link 29 is pivotally connected to the upper end of the actuator 27 and extends horizontally therefrom to be pivotally connected to the arm 26 for actuating the contactor tube 10. The lower end of the actuator is formed into a U-shaped member, as at 30, and has a screw 31 in threaded engagement therewith which screw is engaged by a push rod 32 extending

- upwardly from the diaphragm chamber 22. An adjustment of this screw 31 upon the push rod 32 may be utilized to assist in regulating the tilting angle of the contactor tube 10. 5 Upon such adjustment a set screw 33 is threaded in the actuator 27 for engagement with the screw 31 and is usually set and sealed by the manufacturer before shipment of the switch from the factory.
- 10 The diaphragm chamber 22 comprises flanged portions 34 and 35 which serve to retain the pressure operated member or diaphragm 36 therebetween. Bolts 37 serve to make an air-tight connection between the 15 flange portion 35 and the diaphragm 36. Recesses 38 and 39 are formed respectively in the flanged portions 34 and 35, said recess 39 creating a pressure chamber, pressure being admitted thereto through an opening 40.
- 20 The diaphragm 36 contracts or expands in accordance with the pressure impressed upon it.

A spring 41 opposes the movement of the 25 tilting actuator 27 by the pressure operated diaphragm 36 and is attached to said actuator by some suitable means such as screw 42. The other end of the spring is adjustably secured to the casing 21 by a graduated screw rod 43 which extends through a threaded 30 opening in the wall of the casing and is engaged by a thumb screw 44. The portion of the screw rod 43 upon which the graduation marks are imprinted is flattened and similarly said opening in the wall of the casing 35 has a corresponding flattened portion which serves to hold the screw rod 43 against rotation.

A suitable spring member 45 is secured, 40 as by means of screws, to the tilting actuator 27 and extends vertically within the casing to a point near the top thereof. A screw 46 is threaded in the upper wall of the casing and extends within the casing at a point adjacent the upper end of the spring member 45. A 45 knurled head 47 is secured to said screw on the outside of the casing and has a graduated scale imprinted on the outer face thereof reading from 1 to 6. A pin 48 extends outwardly from the casing 21 and engages the 50 knurled portion of the head 47 to hold the same in a positive position against chance displacement.

It will be apparent that a partial rotation 55 of the knurled head 47 in a clockwise direction will cause the screw 46 to extend a greater distance into the casing and any rotation of the head 47 in the opposite direction will cause the screw to recede outwardly from the casing. In order to prevent the user from 60 tampering with this screw member, a careful adjustment is made in the factory and a set screw 49 is set and sealed on the knurled portion opposite the first graduation to limit the rotation of the head 47, the pin 48 striking against the set screw.

In order to outline the operation of the structure shown in the drawing in a more complete and understanding manner, it will be assumed that the device is associated with an oil burner for heating a steam plant and that the outlet 40 is connected to the steam pressure chamber, the pressure of which is to be regulated. In such a system, the contactor tube 10 will be actuated to an open circuit position to shut off the burner when 75 the steam pressure reaches a high limit hereinafter called "stopping pressure." The contactor tube 10 will be actuated to a closed circuit position to start the burner when the pressure falls to a low limit hereinafter 80 called "starting pressure." The difference in pressure between the starting pressure and the stopping pressure will be termed "pressure change."

These terms, "starting pressure," "stopping pressure" and "pressure change," shall hereinafter be used in the specification and claims for purposes of brevity and clarity only and should not be interpreted as specifying any particular amount of pressure or 90 any particular character of pressure. As will hereinafter be pointed out these pressures may be varied by adjustment.

The graduated screw rod 43 determines the starting pressure and said rod has been 95 illustrated in the drawing as set at 2 pounds. The knurled head 47 determines the pressure change and said head has been illustrated in the drawing as set at 2 pounds. As a result of these settings, when the steam pressure falls to two pounds, the pressure will start to build up within the pressure chamber 39 until it reaches four pounds which is two pounds more than the initial pressure and is the required pressure change, whereafter the 105 pressure will decrease until it reaches two pounds and the action is repeated. Similarly, the starting pressure may be four pounds and the pressure change may be three pounds whereby the pressure will start to build up at 110 four pounds and stop at seven pounds.

In the operation of the mechanism for producing these results, the starting pressure and pressure change may be set at will and the expansible and contractible diaphragm 115 36 will then expand or contract in accordance with the pressure impressed upon it. Assuming that the pressure is of the desired amount, then the contactor tube 10 is in a proper position by manipulation of the spring 41 so that the electrical circuit through said tube is open. If the pressure exerted upon the diaphragm decreases a sufficient amount, the diaphragm will contract and the push rod 32 will move downwardly thereby causing the tilting actuator 27 and its attached parts aided by the spring 41 to tilt to a closed circuit position as shown in Fig. 1.

If the pressure exerted upon the diaphragm 130

36 increases a sufficient amount, the dia-
phragm will expand and the push rod 32
will move upwardly thereby causing the tilt-
ing actuator 27 and its attached parts to tilt
5 against the action of the spring 41 to a posi-
tion where the spring member 45 bears
against the screw 46. A tilting thereafter of
the tilting actuator would be against the
combined spring actions of the members 41
10 and 45. If the screw 46 is set so as to extend
a greater distance into the casing 21, a greater
pressure is required to actuate the contactor
tube 10 into an open circuit position than
would be necessary were the screw set a
15 smaller distance within the casing.

In order to adjust the mechanism to a pre-
determined starting pressure, the thumb
screw 44 is turned until that pressure may
be read upon the graduated scale of the screw
20 rod 43 whereby the spring 41 is under the
proper tension to just counteract the force
of this predetermined pressure on the ex-
pansible and contractible diaphragm 36. Above
25 that predetermined pressure, the graduated
head 47 is adjusted so that a definite pres-
sure is required to actuate the contactor tube
into an off or open circuit position against
the tension of the spring member 45.

While but a single embodiment of this in-
vention is herewith shown and described, it
is to be understood that this invention is not
to be limited to the specific structure shown
therein as various modifications will be ap-
parent to one skilled in the art without de-
parting from the spirit and scope of this in-
vention and, therefore, this invention is to
be limited only by the scope of the appended
claims and the prior art.

I claim:

40 1. In a tiltable switch, a tiltable support,
a tiltable actuator for tilting said support,
pressure responsive means for tilting said
actuator to one position when a predeter-
mined pressure occurs and for tilting said
45 support back to its original position when
the pressure is changed by a predetermined
amount, an adjustable spring member con-
nected to said actuator for determining the
starting pressure at which said support is
50 tilted by said actuator, and means associated
with said actuator for controlling the pres-
sure change, said means comprising a leaf-
spring member having one end only secured
55 to said actuator and an adjustable stop mem-
ber for engagement with the free end of said
leaf-spring member.

2. In a tiltable switch, a tiltable support,
a tiltable actuator for tilting said support,
pressure responsive means for tilting said
60 actuator to one position when a predeter-
mined pressure occurs and for tilting said
support back to its original position when
the pressure is changed by a predetermined
amount, an adjustable spring member con-
65 nected to said actuator for determining the

starting pressure at which said support is
tilted by said actuator, and means associated
with said actuator for controlling the pres-
sure change, said means comprising a leaf-
70 spring member having one end only secured
to said actuator, and an adjustable screw
member for engagement with the free end of
said leaf-spring member.

3. In a tiltable switch, a tiltable support,
a tiltable actuator for tilting said support,
75 pressure responsive means for tilting said
actuator to one position when a predeter-
mined pressure occurs and for tilting said
support back to its original position when
the pressure is changed by a predetermined
80 amount, an adjustable spring member con-
nected to said actuator for determining the
starting pressure at which said support is
tilted by said actuator, and means associated
with said actuator for controlling the pres-
85 sure change, said means comprising a leaf-
spring member having one end only secured
to said actuator, said leaf-spring member
being mounted substantially parallel to said
actuator and the other free end of said leaf-
90 spring serving as a resilient stop for said
actuator, and an adjustable screw member
having a graduated head mounted thereon
whereby said predetermined pressure change
is recorded.

4. In an electric switch, a tiltable support,
a liquid contactor mounted on said support,
a tiltable actuator for tilting said support,
pressure responsive means for tilting said
actuator to one position when a predeter-
100 mined pressure occurs and for tilting said
support back to original position when the
pressure is changed by a predetermined
amount, an adjustable spring connected to
said actuator for determining the starting
105 pressure at which said support is tilted by
said actuator, and additional adjustable
means associated with said actuator for con-
trolling the pressure change, said means com-
prising a leaf-spring member having one end
110 only secured to said actuator and an adjustable
stop member for engagement with the free
end of said spring member.

In witness whereof, I have hereunto sub-
scribed my name.

LOUIS A. M. PHELAN.
